[57] CLAIM

The ornamental design for a ganging mechanism for chairs,
as shown and described.

DESCRIPTION

FIG. 1 is a top, front and left side perspective view of a
ganging mechanism for chairs showing my new design in
the assembled position;FIG. 2 is a perspective view of the ganging mechanism for
chairs illustrated non-assembled;

FIG. 3 is a top plan view thereof assembled together;

FIG. 4 is a right side elevational view thereof assembled
together, the left side being a mirror image;FIG. 5 is a bottom plan view thereof assembled together;
and,

FIG. 6 is a rear elevational view thereof.

The chairs shown in broken lines in FIG. 1 are for illustrative
purposes only and do not form part of the claimed design.
